UNITED STATES PATENT OFFICE.

ARCHIE GAGNON, OF PAWTUCKET, RHODE ISLAND, ASSIGNOR OF ONE-HALF TO
CHARLES G. GREENHALGH, OF PAWTUCKET, RHODE ISLAND.

LOOM ATTACHMENT.

Application filed June 3, 1926. Serial No. 113,423.

This invention relates to certain new and useful improvements in loom attachments and pertains more especially to an attachment wherein the feeler which operates to contact with the bobbin, due to the swing of the lay, upon the yarn or filling reaching a predetermined diameter effects operation of a replenishing device to place either a new shuttle with a full bobbin, or a full bobbin, in the shuttle of the loom.

The primary object of the invention is to provide a device of this character which has improved means for preventing constant contact of the feeler with the bobbin throughout the motion of the lay, or for bringing the feeler into periodic engagement with the yarn, and more specially for permitting the feeler to contact with the yarn but one in thirty picks until the yarn reaches a predetermined diameter just prior to its depletion.

A further object of the invention is to provide an attachment of the type set forth, which is of simple, economical and compact construction, positive in operation and capable of being easily and quickly applied to the loom.

In the drawings

Fig. 1 is a perspective view of the invention;

Fig. 2 is a detail view of the takeup worm gear showing the invention as associated therewith.

Figs. 3, 4, 5, are detail views showing the feeler and the bobbin yarn during the various stages of depletion of the yarn; and

Fig. 6, is a detail view of the bevelled end of the operating rod for the feeler.

In proceeding in accordance with the present invention a dog 1 is secured to a side face of the take-up worm gear 2 so as to project at one end beyond the worm teeth. A horizontal bracket 3 is suitably attached to the lower part of the loom and a horizontal bracket 4 is likewise attached to the top part of the loom. The brackets are perforated to slidably support a vertical rod 5, the latter having its lower portion offset at 5' and having its lower end flattened and bent at substantially right angles to form a finger 6 the free end of which is in the path of movement of the dog 1. A collar 7 is adjustably mounted on the offset part 5' of the rod and is engaged by one

end of the coil spring 8 which latter surrounds the offset part 5' of the rod, the other end of the spring seating on the lower bracket 3. The upper free end of the rod 5 is tapered or beveled as indicated at 9. The feeler F has a notch 10 formed in a side thereof in which the beveled end 9 of the rod 5 is received, the notch forming a transversely disposed wall or abutment with which the beveled end 9 of the rod 5 engages.

In operation and as heretofore practised in the art, the take-up worm gear 2 makes one revolution in approximately thirty picks of the loom, that is to say the feeler F contacts with the yarn on the bobbin approximately thirty times to one complete revolution of the gear. This has been found to be detrimental in that such contact injures the yarn on the bobbin, and to overcome this objection it will be seen that by the present invention, the dog 1 upon the gear 2 engaging the finger 6 of the rod 5, depresses the latter thereby releasing the feeler. The feeler then contacts with the practically full bobbin and is immediately returned to position out of engagement with the yarn upon the rod being released by reason of the rotation of the gear 2, whereby the upper end of the rod enters the notch 10 in the side of the feeler and is moved by the bevelled end 9 of the rod out of contact with the yarn, until the rotating movement of gear 2 again brings the dog 1 into engagement with the finger 6 to release the feeler, whereupon the latter will repeat its above described action until the diameter of the yarn on the bobbin has decreased to that shown in Fig. 5. Thereupon the feeler contacts with the top of the rod and slides thereover, and maintaining its engagement with the yarn until the diameter of the latter reaches the point where the change motion is brought into action and either a new shuttle with a full bobbin or a new bobbin to the shuttle in the loom is supplied.

From the foregoing it will be seen that the invention, in brief thus brings the feeler into periodic or intermittent engagement with the yarn and more specifically once only during a complete revolution of the take-up gear, as distinguished from the prior art in which the feeler contacts with the yarn approximately thirty times to each revolution of such gear. The present invention

tion therefore not only effects intermittent engagement of the feeler with the yarn, but also when the yarn reaches a predetermined diameter, permits the feeler to have constant engagement with the yarn so as to assure the change motion being brought into operation upon depletion of the yarn. It will be further seen from the foregoing that the bevelled end of rod 5 acts as a cam which forces the feeler back from the yarn at all times until the yarn approaches depletion. This insures the feeler being maintained out of contact with the yarn for twenty nine picks. After the change motion is brought into play and a full bobbin is inserted in the loom, the increased diameter of the yarn will force the feeler away from the shuttle to an extent sufficient for the end 9 of the rod to engage the notch 10 of the feeler and thereby hold the latter out of contact with the yarn.

What I claim as new and desire to secure by Letters Patent is:

1. A loom attachment including a feeler having a side notch, a vertically sliding spring pressed rod having a rigid vertically disposed bevelled upper end and an outwardly extending finger at its lower end, the bevelled upper end being formed to engage in said side notch of the feeler, spring means for upwardly tensioning the rod, and a dog formed for securing to the take-up worm gear and having an end engageable with the finger to depress the rod thereby to release the feeler upon each revolution of the gear, the bevelled end of the rod being formed to cam against and move the feeler out of engagement with the yarn upon upward movement of the rod.
2. In combination with a feeler having a transversely disposed wall, a bodily movable member having a rigid vertically disposed cam-forming portion engageable with the said wall to move the feeler away from the bobbin upon upward movement of the member, means to mount the member so that its cam-forming portion is movable to underlie the feeler, and means to periodically actuate the member to permit the feeler to move toward the bobbin, said wall being disposed so that as the yarn approaches depletion, the wall will be out of alignment with the cam-forming portion and the feeler will slide over the latter and be unaffected thereby.
3. In combination with a notched feeler and the take up gear of a loom, spring pressed bodily compressible means having a rigid vertically disposed tapered part engageable with the wall defining the notch to cam against side wall and move the feeler away

from the yarn upon each engagement therewith until the latter reaches a predetermined diameter, said tapered part being movable to lie beneath the feeler, and said notch being positioned so that after the yarn reaches said predetermined diameter the notch will be out of register with said tapered part whereby the feeler can move over said part and engage the yarn so as to bring the change motion into play upon depletion of the yarn, and means actuated by the gear to operate the compressible means upon each revolution of the gear.

4. In combination with a feeler having a transversely disposed wall, a slidable spring pressed rod having a rigid vertically disposed cam-forming portion at its upper end engageable with the said wall to move the feeler away from the bobbin upon upward movement of the rod, and means to periodically actuate the rod to disengage same from and to permit the feeler to move toward the bobbin, said wall being disposed so that as the yarn approaches depletion, the wall will be out of alignment with the cam-forming portion and the spring will hold the said portion engaged with the under face of the feeler and will allow the latter to slide thereover.

5. In combination with a feeler having an abutment, a vertically and bodily movable member having a rigid cam part engageable with the abutment to move the feeler away from the bobbin upon upward movement of the member, said cam part being movable to lie beneath the feeler, means to periodically actuate the member to release same thereby to permit the feeler to move toward the bobbin, said abutment being disposed so as to be out of alignment with said cam part as the bobbin approaches depletion whereby to permit the feeler to have continuous engagement with the bobbin, and means to move the member upwardly.

6. In combination with a feeler having an abutment, a bodily movable tensioned member having a rigid cam part engageable with the abutment to move the feeler away from the bobbin upon engagement of the cam part with the abutment, and means to effect periodic bodily movement of the member to release the cam part thereof from the abutment thereby to permit the feeler to move toward the bobbin, said abutment being disposed so as to be out of alignment with said cam part as the bobbin approaches the feeler to permit the feeler to have continuous engagement with the bobbin.

In testimony whereof I have hereunto signed my name to this specification.

ARCHIE GAGNON.
